PACKAGING MACHINE

John Hohl, Olav Bjering, and Charlton F. Whittier, Toledo, Ohio, assignors to Owens-Illinois Glass Company, a corporation of Ohio

Application March 24, 1939, Serial No. 263,948

6 Claims. (Cl. 226—61)

Our invention relates to packaging liquids or other materials. In its preferred form it comprises a machine adapted for filling bags or containers with a liquid, as, for example, a lubricating oil, and then sealing the bag.

An object of the invention is to provide a new and practical machine for filling collapsible bags or containers with a liquid, in accordance with which the liquid is introduced as by means of a nozzle into the collapsed container, and causing the latter to be gradually expanded by the entering liquid while preventing or restricting the entrance of air.

Another object of the invention is to provide a practical machine for rapidly filling containers and for sealing the filled containers.

A further feature of the invention consists in the provision of a novel form and construction of the nozzle through which the liquid is injected into the containers.

An object of the invention is to provide a filling nozzle so constructed and operated in such manner as to prevent or reduce to a minimum the drip from the nozzle between successive filling operations, and further to control any drip that may occur and direct it away from the containers.

A further object of the invention is to provide novel sealing mechanism by which each container when filled is subjected to more than one sealing operation and in a manner to insure a strong, effective and reliable seal.

Other objects of the invention will appear hereinafter.

Referring to the accompanying drawings which illustrate a preferred form of our bag filling machine and which, as hereinafter described, is especially designed for filling collapsible bags with oil or other liquid:

Fig. 1 is a perspective view of the filling machine, parts being shown in section;

Fig. 2 is a part sectional elevation of the machine looking in a direction at right angles to that of Fig. 1;

Fig. 3 is a sectional plan view, the section being taken at the line 3—3 of Fig. 2;

Fig. 4 is a part sectional elevation on a larger scale, showing a portion of the feeding mechanism, the filling nozzle and clamping means for clamping a bag to the nozzle;

Fig. 4—A is a detail view showing means for holding the end gates of the trays in closed position;

Fig. 5 is a fragmentary part sectional elevation showing the tray carrying turret, mechanism for

rotating the same, bag sealing mechanism, and means for expelling air from the bag;

Fig. 6 is a fragmentary sectional elevation showing a cam and motion transmitting mechanism actuated thereby for operating the bag clamping and sealing devices;

Fig. 7 is a view of the mechanism shown in Fig. 6, looking in a direction at right angles to that of Fig. 6;

Figs. 8 to 11 are diagrammatic views illustrating the sealing operations;

Fig. 8 shows the first clamping and sealing means;

Fig. 9 shows the means for effecting a second sealing operation; and

Figs. 10 and 11 illustrate in plan and elevation respectively, the sealed end of a package.

The machine in the form illustrated comprises in general terms, a platform or base 10 supported on a framework 11, a vertical tubular column 12 having a fixed mounting in the base 10, a superstructure including an upper platform 13 supported in part by the column 12, an electric motor 14, a hopper 15, a filling nozzle 16, means including a cylinder 17 and piston 18 for drawing charges of oil from the hopper and forcing such charges through a pipe 19 to and through the filling nozzle, driving mechanism including speed reduction gearing interposed between the motor 14 and the piston 18 for driving the latter, a series of trays 20 for receiving the bags as they are filled, a turret 21 on which the trays are mounted, mechanism for imparting step by step rotation to the turret, bag clamping and sealing units 22 and 23 (Fig. 3), and means for actuating said units, including a cam 24 (Figs. 6 and 7) and motion transmitting mechanism between the cam and said units including a shaft 25 which is reciprocated within the hollow stand 20 and 12.

The machine will now be described in detail as constructed and used for filling bags 30 with oil and sealing and discharging the bags. A supply of oil is continuously maintained within the hopper 15 and is drawn in measured charges from the hopper into the cylinder 17 by retraction of the piston 18. Each charge is forced by the forward movement of the piston through the valve 31 (Figs. 1 and 4), pipe 19 and feeding nozzle 16 into a bag 30. The motor 14 operates through speed reduction gearing within a gear casing 32 (Fig. 1) to rotate a drive shaft 33 and disk 34 keyed thereto. A rock arm 35 mounted to rock about a pivot 36 is actuated by means 55 of a roll 37 on the disk 34 engaging a slot 38.

in the arm. A connector 40 provides a connection between said arm and the piston rod 39 of the piston 18. The roll 37 is adjustable radially of the disk 34 by adjusting means including a screw rod 41, thus permitting the length of the piston stroke to be adjusted to adjustably vary the volume of the charges of oil.

The valve 31 as shown in Fig. 4 is a two-way valve adapted to place the cylinder 17 alternately in communication with the funnel 15 and pipe 19. The valve is held in the Fig. 4 full line position while the piston 18 is moved outwardly for drawing a charge of oil into the cylinder. The valve is then automatically rotated to the dotted line position (Fig. 4) to cut off communication with the funnel and open a passageway from the cylinder to the pipe 19. The means for oscillating the valve 31 includes a cam 42 (Fig. 1) fixed to the shaft 33 for rotation therewith, said cam engaging a cam roll 43 on a disk 44 mounted to oscillate about the axis of the shaft 33. An arm 45 formed on and depending from the disk 44, is connected through a rod 46 (Figs. 1 and 4) with an arm 47 of a bell crank fulcrumed at 48. The other arm 49 of the bell crank is connected through a link 50 to a rock arm attached to the valve 31.

The bell crank 47, 49 also operates through mechanism which will now be described to actuate means for clamping the bag 30 to the filling nozzle and holding the bag during the filling operation. Such clamping means includes a gripping pad 51 (Fig. 4) made of rubber or the like, said pad mounted in the lower end of a rock arm 52 attached to a rock shaft 53 journaled in an arm 54. A second rock arm 55, fixed to the rock shaft 53, is held under the tension of a coil spring 56, thereby causing a yielding pressure of the gripping pad 51 against the nozzle. A post 57 adjustably mounted in the arm 54 and clamped in position by a set-screw 58, has pivotally connected thereto at its upper end, a rock arm 59. The outer end of the rock arm is pivoted at 60 to one end of a rod 61, the opposite end of which is pivoted at 62 to the bell crank arm 49. The arm 59 carries a pin 63 which engages a slot 64 in a vertically disposed arm or link 65, the lower end of which has a pivotal connection 66 with the arm 55.

It will be seen that with the parts in the position shown in full lines in Fig. 4, in which the valve 31 cuts off the supply of oil to the filling nozzle, the gripping pad 51 is held away from the nozzle 16, permitting the operator to slip a bag into filling position with the nozzle projecting into the fill opening of the bag. When the bell crank 47, 49 operates to reverse the valve 31 preliminary to filling the bag, the rod 61 is moved downward. As soon as this downward movement commences, the spring 56 is free to swing the arm 55 downward to the broken line position, thereby moving the gripping pad 51 into gripping position. The pin 63 is carried downward along the slot 64 during the continued movement of the bell crank and just before such movement is completed, the pin 63 engages the lower end of the slot and operates positively through the link 65 to increase the gripping pressure of the pad 51 and thus securely hold the bag in contact with the nozzle during the filling operation. The gripping pressure of the pad 51 may be adjusted by adjusting the post 57 up or down in the arm 54.

Connected to the lower end of the pipe 19 is an extension in the form of an elbow 67 enlarged to form a chamber 68 into and through which the

oil is directed. Owing to the capacity of this chamber, the movement of the oil is sufficiently slow to cut down turbulence and reduce foaming of the oil to a minimum. The nozzle proper may be mounted on the elbow 67. The lower end 69 of the nozzle has both its outer and inner walls tapered. A plug 70, which serves as a valve for closing the nozzle, is also tapered to correspond with the taper of the inner nozzle wall and provides therewith an effective seal.

The plug 70 is formed on the lower end of a tubular rod 71 which extends upwardly through the chamber 68. The elbow 67 has an extension 72 which provides a bearing for the rod 71 and also forms a support for the arm 54. A collar 73 is mounted on the rod 71 in the path of a finger or arm 74 formed integral with the arm 59. When the valve 31 is swung downward to bag filling position, the finger 74 is swung upward to the broken line position, thereby engaging the collar 73 and withdrawing the plug 70 for opening the nozzle. When the valve 31 is reversed to close the pipe 19, the valve plug 70 is lowered by a coil spring 75 and closes the nozzle, thereby preventing dripping of residual oil.

Air may be supplied through a hose 76 to the valve stem 71 and through the latter for breaking up air bubbles or foam which may accumulate at the mouth of the bag owing to agitation of the oil during the filling operation. This air may be supplied from any suitable source (not shown) and is controlled by any suitable means for periodically supplying a puff of air and applying it within the open end of the filled bag. The lower end of the nozzle 16 and plug 70 are especially shaped to cause any residual oil which may seep through while the plug is in closed position, to collect at a point away from the bag or wall of the tray. For this purpose the end surfaces of the plug and nozzle are inclined toward a central point 70^a at which such oil will accumulate. This prevents any such oil from soiling the end of a bag as the latter is placed in position on the nozzle.

The trays 20 are arranged in an annular series on the turret or carriage 21 and are adjustably held in position as by means of clamping bolts 77 (Fig. 2). The turret is given an intermittent step by step rotation for bringing the trays in succession to the filling station and holding them at rest during the filling operation. The trays are downwardly and outwardly inclined, preferably at an angle of about 45°. The nozzle 16 and valve stem 71 are likewise inclined at the same angle so as to align with each tray as the latter is brought to rest at the filling station.

The mechanism for intermittently rotating the turret 21 includes a vertical drive shaft 78 driven from the motor 14 through a train of gearing including bevel gears 79 and 80 at the upper end of the shaft. On the lower end of the drive shaft is a bevel gear 81 (Figs. 2 and 3) meshing with a bevel gear on a horizontal shaft 82 journaled in a bracket 83 beneath the platform 10. Intermeshing gears 84 and 85 are secured respectively to the shaft 82 and a parallel shaft 86. The latter operates through bevel gears 87 to drive a vertical shaft 88 for operating a Geneva drive. The latter may be of conventional construction and as shown includes a gear wheel 89 bolted to the hub 90 (Fig. 2) of the turret 21. Keyed to the upper end of the shaft 88 is an arm 91 carrying a roll 92 (Fig. 5) for engaging the radial slots 93 in the Geneva wheel for rotating the latter step by step. The shaft 88 also carries the usual

locking plate 94 to engage the locking surfaces 95 on the Geneva wheel and lock the latter while the arm 91 is disengaged.

The turret is advanced one step, namely, the angular distance between centers of two adjacent trays, each time the drive shaft 78 is given a complete rotation. The drive shaft is rotated intermittently, being under the manual control of the operator and is automatically brought to rest at the completion of each rotation by means of a stop switch 96 (Figs. 1 and 2) in the controlling circuit of the motor 14, said switch being operated by an arm 97 on the drive shaft 78. The switch is released to start the machine, by means of a push button 98 connected to the switch through a push rod 99. In the particular construction shown there are eight trays mounted on the turret and each tray is brought to stations A, B, C, D, E, F, G, and H in succession by the rotation of the turret.

The sealing units 22 and 23 and their operating mechanism will now be described. As shown in Fig. 3 these units are located respectively at stations C and D. The two units are carried on a bracket comprising a hub 100 having a fixed mounting on the column 12, and radially disposed arms 101, 102 and 103 extending outwardly and downwardly from the hub. Journalled in the arms 102 and 103 is a rock shaft 104 to which is secured a rock arm 105, the outer end of which is bifurcated to engage a pin or roll 106 carried by a sleeve 107 which has a limited up and down movement on the column 12. The sealing unit 22 comprises upper and lower blocks 22^a and 22^b respectively (see Figs. 2, 5 and 8) which function as a pair of clamping jaws between which the filling end of the container is gripped during the sealing operation. The upper block 22^a is carried on a bracket 108 in the form of a bell crank lever mounted to rock on the shaft 104. A rod 109 connected to the sleeve 100 extends outwardly through an opening in the bracket 108 and has mounted thereon a coil spring 110 which is held under compression and applies outward pressure against the bracket. Stop nuts 111 threaded on the rod 109 determine the position of the block 22^a. The lower block 22^b includes a resilient pad 112 of "Neoprene" or other resilient or rubber like material which serves as a resilient backing for the heater block 22^a. The head 22^b is carried on a rock arm 113 keyed to the shaft 104.

Except during the sealing operation the lower head 22^b is held in its retracted position (Fig. 5) by means of a coil spring 114 (Fig. 2) mounted within the tubular column 12. The spring is connected to the rod 25 and exerts a continuous upward pull thereon. The pin 106 extends through a slot 106^a in the column 12 and is connected to the rod 25, permitting the sleeve 107 to be held in its lifted position (Fig. 5), thus holding the head 22^b in its retracted position.

Means for swinging the head 22^b upward to clamping and sealing position includes the cam 24 (Figs. 6 and 7) which engages and operates a bell crank 115 fulcrumed on a bracket 116, the bell crank including an arm pivotally connected with the lower end of the shaft 25. The rotation of the cam 24 operates through the bell crank to draw the shaft 25 downward and thereby swing the lower sealing block 22^b upward to engage the mouth end of the bag and clamp it against the upper sealing block 22^a. The final upward movement of the lower block operates to lift the block 22^a a short distance, swinging the bracket

108 against the compression force of the spring 110 so that the blocks are held in clamping and sealing position with a yielding pressure. Within the block 22^a is an electric heater 117 (Fig. 8) and a thermostat 118 which automatically controls the temperature of the sealing block by regulating in a conventional manner, the current supplied to the heater. The electric current is supplied to the heater through conductors carried in a cable 119 leading to the heater from any suitable source of current supply.

The bags 30 which when applied to the machine for filling, are in a deflated or collapsed condition, may be of rectangular construction, 15 including the major upper and lower faces 30^a and 30^b respectively (Fig. 1) and the intermediate comparatively narrow side walls 30^c which may be integral with the major walls and may be in the form of infolds or gussets. The bag 20 may be made from a single strip of material folded to the form described and is sealed along the side and bottom end. The upper end may have corner portions 120 (Fig. 10) sealed, leaving a fill opening 121 therebetween, said opening being considerably narrower than the bag and of a size to fit closely over the filling nozzle. The nozzle being tapered facilitates the attaching of the bag thereto, as well as providing an approximately air-tight seal. The bag 30 may 25 be made of a thermoplastic material such as "Pliofilm" which is well adapted for such purpose. When the end of the filled bag is clamped between the heads 22^a and 22^b, the heat applied to the bag serves to soften the material and seal the bag.

In order to supplement the sealing operation of the sealing unit 22 and thereby insure a perfect and reliable seal, a second sealing operation is effected by the sealing unit 23 which in general 40 is substantially similar in construction and operation to that of the unit 22 as above described. The sealing unit 22 operates at the station C and the unit 23 at the station D. By reference to Fig. 9 it will be seen that the bag contacting surfaces 45 of the sealing elements are formed with complementary shoulders or offsets 122 so as to form a bend or offset 123 (Fig. 11) in the sealed end of the bag. This results in a more reliable seal, decreasing any likelihood or possibility of the superposed plies of the sealed material spreading or developing a leak. The first sealing element 22 may contact with the end portion of the bag, the area of contact extending from the end edge rearwardly to a line 124. The second sealing element 50 may be applied to a narrower end strip, the inner edge of which is defined by a line 125. Preferably a somewhat higher temperature is applied by the second sealing unit. This tends to soften the material a greater degree, insuring a good seal where the number of superposed plies of material is increased by the infolds or gussets and also at the lines of said folds.

Mounted on the head 22^a is a presser device 126 (Figs. 2 and 5) which engages over the upper surface of the bag at the sealing station and compresses the end portion of the bag sufficiently to expel most of the air that may be contained in the bag. This takes place just before the sealing operation. Also associated with the first sealing unit is a presser plate 127 for applying pressure to the filled bag and expelling air therefrom. The plate 127 is carried on an arm 128 connected to a rock shaft 129 mounted on the sealing unit. A rock arm 130 also attached to the rock shaft 129 is connected through a link 131

with an arm 132 mounted to rock with the shaft 104. When the shaft 104 is rocked to swing the block 22^b upward to sealing position, it operates through the linkage just described to swing the presser plate 127 downward against the filled bag and compress it so that most of the air which may be in the bag is expelled just before the sealing takes place.

Each of the trays 20 is provided at its lower end with an end gate 133 hinged to swing downward for discharging the package at the discharge station G. The gates have spring hinges 133^a (Fig. 4-A) to normally hold them up in closed position. The gates are opened in succession at the discharging station by the upward movement of the cam actuated rod 25 operating through means shown in Figs. 1 and 2, as follows:

A lever 134 having a fulcrum 135 intermediate its ends is connected through a link 136 and pin 137 to the lower end of the shaft 25. The lever is connected at the end opposite the link 136 through a link 138 to a rock arm 139 which engages a lug 140 on the hinge rod of the end gate 133 for swinging the gate downward and thereby permitting the discharge of the package by gravity onto an inclined chute or platform 141 (Fig. 1).

In order to securely hold each end gate 133 in closed position while at the filling station, a holding device in the form of a disk 142 (Figs. 1 and 4-A) is mounted by means of a bracket 143 on the platform 10 and is spring-held as by means of a leaf spring 143^a in position to engage the end gate of each tray as the latter is brought to the filling station. This prevents the possibility of the end gate opening slightly when the bag slides into position on the tray which might result in pinching the film. That is to say, the spring 143^a is sufficiently stiff to counteract the force applied to the gate when the bag strikes it, thus positively holding the gate closed. Such opening of the gate would also prevent it from holding the bag at the proper height for correct sealing.

The operation of the machine will be understood from the foregoing description but may be summarized as follows:

While the machine is at rest the operator places a bag in position at the filling station A, with the nozzle 16 projecting into the fill opening, the bag at this time being in a deflated, flat condition. The operator then pushes the switch button 98, thereby releasing the limit switch and starting the motor 14. The valve 31 is at this time in the Fig. 4 position. The motor operates to move the piston 18 outwardly, drawing a charge of oil into the cylinder 17. The cam 42 then operates as before described to reverse the valve 31 so that as the piston 18 moves inward, a charge of oil is forced downward to the filling nozzle and into the bag. During this filling operation the bag is automatically held clamped to the nozzle by the clamping pad 51 (Fig. 4). Also, while the bag is being filled, the plug 70 in the filling nozzle is held in its retracted position, permitting a free flow of oil into the bag. Then, as the filling operation is completed and the valve 31 reversed, the plug is automatically moved to closed position for preventing oil dripping. The turret carrying the trays remains stationary until the filling operation has been completed and is then advanced one step by the Geneva drive. The clamp 51 is automatically released as the plug 70 closes the nozzle, permitting the filled

bag to slide downward by gravity into the tray, thereby releasing it from the nozzle. The Geneva drive now operates to rotate the turret, advancing the trays one step. This brings the filled bag to station B and the turret is automatically stopped with the next tray at the filling station. When the filled bag reaches station C, the sealing unit 22 operates to seal the bag in the manner heretofore described, the pressure plate 127 operating as the sealing jaws are coming together, to expel the major portion of any air contained in the bag. At station D the second sealing operation takes place. The filled bag remains in its tray until station G is reached, at which the end gate is automatically opened and the package discharged by gravity from the machine.

Modifications may be resorted to within the spirit and scope of our invention as defined in the appended claims.

We claim:

1. A packaging machine comprising means for filling a bag with a commodity at a filling station, a tray positioned and arranged to support the bag during the filling thereof, a traveling carriage on which the tray is mounted and by which the tray is carried to and from the filling station, said tray including a hinged end gate at the lower end thereof, a stationary holding device positioned to contact the gate and hold it closed while the tray is at said station, a spring yieldingly holding the gate closed while the tray is away from said station, and automatic means for opening said gate against the tension of the spring and permitting the package to be discharged from the tray by gravity.

2. A packaging machine comprising a carriage rotatable about a vertical axis, a tray mounted thereon in an inclined position and adapted to support a container, said tray having an end gate hinged thereto at the lower end of the tray, means for rotating the carriage and thereby bringing the tray to a filling station and thereafter to a discharging station, a holding device arranged to engage the end gate and hold it closed while the tray is at the filling station, a spring yieldingly holding the gate closed during the rotation of the carriage, and means at the discharging station to open said end gate against the tension of said spring and permit the discharge of the filled container.

3. A packaging machine comprising a carriage rotatable about a vertical axis, a tray mounted thereon and adapted to support a container, said tray having an end gate at the lower end thereof, means for rotating the carriage step by step and thereby bringing the container to a filling station and thereafter to a discharging station, means for filling the container while supported by the tray at said filling station, a spring yieldingly holding said end gate closed during the rotation of the carriage, means at the discharging station for opening said end gate against the tension of the spring while the tray is at rest at the charging station and thereby permitting the discharge of the filled container, a roll at the filling station mounted separately from the carriage in position to engage the outer surface of the end gate while the carriage is at rest with the tray at the filling station and thereby prevent accidental opening of the end gate.

4. A machine of the character described comprising, in combination, a carriage, means for rotating it about a vertical axis, a tray mounted thereon, said tray having a hinged end gate at

its lower end, spring means for holding the gate normally closed during the rotation of the carriage, means for delivering a package to the tray when the latter is in a predetermined position and allowing the package to move downward along the tray and be arrested by said end gate, holding means positioned to engage the outer side of said end gate when the tray is in said predetermined position and thereby prevent opening of the end gate when it is struck by the descending package, and means operating against the tension of said spring means for opening the end gate at a delivery station and permitting the package to be discharged from the tray by gravity.

5. A machine of the character described comprising, in combination, a carriage, means for rotating it about a vertical axis, a tray mounted thereon, said tray having a hinged end gate at its lower end, spring means for holding the gate normally closed during the rotation of the carriage, means for delivering a package to the tray when the latter is in a predetermined position and allowing the package to move downward along the tray and be arrested by said end gate, a stationary holding device in position to engage

10 the end gate and positively hold it against opening movement by the descending package, and means operable to open the end gate in opposition to said spring holding means after the tray has advanced beyond said stationary holding device to a delivery station and thereby permitting the package to be discharged by gravity from the tray.

15 6. A packaging machine comprising a carriage rotatable about a vertical axis, an annular series of downwardly and outwardly inclined trays on the carriage, each tray having an end gate at the lower end thereof and spring means for holding the end gate normally closed, means for rotating the carriage step by step, means for delivering a package to each tray at a station and permitting the package to slide downward by gravity until arrested by the end gate, a stop device having a stationary mounting in position to hold the end gate closed at said station, and means operable in opposition to said spring holding means for opening each end gate in succession while the associated tray is at rest at a discharging station.

JOHN HOHL.
